UNITED STATES PATENT OFFICE.

JULIAN A. MANN, OF NEW YORK, N. Y.

DESIGN FOR A DUSTER.

Application filed May 23, 1927. Serial No. 22,132. Term of patent 7 years.

To all whom it may concern:

Be it known that I, JULIAN A. MANN, a citizen of the United States, residing in the borough of Manhattan, city, county, and State of New York, have invented a new, original, and ornamental Design for Dusters, of which the following is a specification, reference being had to the accompanying drawing, forming part thereof.

I claim:

The ornamental design for a duster, as shown.

JULIAN A. MANN.
